PIVOTED MULTIPLE LEVER CAP GRIPPING
WRENCH

Asher M. Wolfe, Bloomsburg, Pa.

Application August 6, 1946, Serial No. 688,677

6 Claims. (Cl. 81—3.44)

1

This invention relates to a new and improved kitchen aid or the like, particularly adapted for removing or tightening jar tops, screw tops on bottles, corks, and other stoppers, and for cutting the tops out of cans.

I am aware that many such implements have been proposed in the past, but as far as I know, there has never been available a satisfactory tool of the class described which is simple and reliable in operation, inexpensive to manufacture, and satisfactory for the use intended.

It is an object of this invention to provide a tool of the class described which is adjustable to fit any size jar or bottle likely to be found in the kitchen or in the household; which is simple in operation so that no skill or practice is required to operate it; and one which can be manufactured with a few simple operations, is easily and quickly assembled, and which will be rugged and not likely to fail under normal conditions of use.

It is a further object of this invention to provide such a tool in which all of the parts are simple punch press parts so that no elaborate castings are required, and only the simplest tools are necessary to make it.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, will best be understood by reference to the specification and accompanying drawing, in which

Fig. 1 is a perspective view of the tool in accordance with my invention,

Fig. 2 is a bottom plan view thereof, and

Fig. 3 is a section on lines 3—3 of Fig. 1.

In accordance with my invention, the tool is made of multiple levers provided with gripping jaws so arranged that as the levers are actuated the jaws expand or contract, enabling the tool to operate on a wide range of jar sizes, gripping the top at several points around the periphery thereof in much the same way as the human hand grasps it in removing or replacing the top.

Referring now more particularly to the drawing, the tool is formed of a first pair of levers 10 and 11 pivoted at point 12 intermediate the ends and preferably nearer one end than the other, the longer lever ends forming the handle and the shorter lever ends being folded downwardly as at 11a and 12a to provide one pair of gripping jaws.

2

Preferably also the handle ends are bent inwardly; that is, in a direction toward each other, at points 13 and 14 to enable the operator to grasp the handles more conveniently, and the length of the handle ends is enough so that the operator can hold the tool readily.

A second pair of levers 20 and 21 is provided, this second pair being pivoted adjacent one end, as at 22, and the free ends of levers 20 and 21 are preferably bent downwardly as at 20a and 21a to provide another pair of gripping jaws. Levers 20 and 21 are pivoted to levers 10 and 11 at points 23 and 24, which, it will be noted, are intermediate the jaw ends of levers 20 and 21 and pivot 12, and likewise intermediate the jaw ends of levers 10 and 11 and pivot point 12.

It will be observed that the four pivot points 12, 22, 23, and 24 define a parallelogram for all positions of the wrench, and for one adjustment 20 of the wrench (as in Fig. 2) these four points are the points of a square. The gripping jaws already mentioned will be observed to lie entirely on the outside of this parallelogram, and this is true for any adjustment of the wrench.

25 In order to obtain a better grip on larger jars, the inner surface of jaws 11a, 12a, 20a, and 21a may be provided with scoring or otherwise roughened surfaces, and in forming the wrench these jaws are bent at the free ends of the levers on a line 30 which makes a slight angle to the perpendicular to the center line. This provides that the gripping jaw surface is more nearly tangent to any circle concentric with the point of intersection of lines connecting opposite pivot points. This will 35 best be observed in Fig. 2.

It will be noted that there is a certain minimum size which is the smallest that the gripping jaws already mentioned can hold. In order to provide for operating on objects of smaller size, I may 40 provide a second set of jaws, as at 10b, 11b, 20b, and 21b, within the four pivot points. These may be formed by cutting out arcuate portions of the levers and serrating the inner edges for better grip. If desired, an additional set of jaws (not shown) may be formed on the inner side of levers 13 and 14, but on the handle side, and jaws 10b, 11b, 20b and 21b may be omitted.

To provide for cutting the tops out of cans, can cutter 30 may be provided. This may, for instance, be in the form of a short sleeve slidingly mounted on lever 21 between gripping jaw 21a and pivot 23, and having downwardly projecting cutter blade 31.

In the manufacture of the tool I prefer to use 55 so-called strip-stock, usually steel, which may

be coated or plated with tin or chromium, and the various levers may be formed by simple stamping operations requiring no elaborate or expensive tools. It will be observed that, aside from the rivets, the tool comprises only five parts, the two handle levers, the two shorter levers, and the can cutter. If the can opener is omitted, only four parts other than the rivets are required. In assembling, it is only necessary to insert the rivets through holes at the pivot points and head them in position, this operation being done so that there is little play or lost motion at these points, and yet the wrench may be opened and closed without effort.

In order to tighten or loosen a jar top, the jar is placed with its top within the outer gripping jaws, if large enough, as indicated in Fig. 2. The operator then exerts pressure on the handle portions of levers 10 and 11 with one hand, grasps the body of the jar with the other, and turns the top as required. In case the top or stopper is too small to be gripped by the outer jaws, it may be gripped with the inner jaws and tightened or loosened, as desired.

To open a can, can cutter 30 may be moved in away from the rim of the can, then the wrench tightened on the rim of the can as indicated in Fig. 2, and the cutter slid outwardly until the point of the cutter engages the top of the can just inside the rim, whereupon pressure is applied to puncture the can.

At this point the pressure on the handles will be released somewhat so that the can and wrench may be easily turned with respect to each other. It is only necessary then to rotate the can, applying only sufficient pressure to the wrench so that it does not slip off the can, and as the can is rotated with respect to the wrench, the cutter will cut the top out of the can.

In the specification I have explained the principles of my invention and the best mode in which I have contemplated applying those principles, so as to distinguish my invention from other inventions; and I have particularly pointed out and distinctly claimed the part, improvement, or combination which I claim as my invention or discovery.

While I have shown and described certain preferred embodiments of my invention, it will be understood that modifications and changes may be made without departing from the spirit and scope thereof, as will be clear to those skilled in the art.

I claim:

1. A gripping and squeezing tool comprising, in combination, a pair of relatively long levers pivoted together intermediate their ends, a second pair of relatively short levers pivoted together adjacent their ends, said two pairs of levers being pivoted together intermediate their ends and the pivot point of each pair, each of said levers having a gripping jaw extending laterally therefrom at the free end, said gripping jaws being adjacent to but outside the parallelogram formed by lines joining the pivot points.

2. A gripping and squeezing tool comprising, in combination, a first pair of levers pivotally

connected at a point nearer one end than the other, a second pair of levers pivotally connected at their extremities, said pairs of levers being pivotally connected on the shorter arms of said first pair of levers and intermediate the free ends and the pivot point of said second pair, and gripping jaws extending from the shorter ends of said first pair of levers and from the free ends of said second pair of levers, said jaws lying outside the parallelogram formed by lines joining the pivot points.

3. A gripping and squeezing tool comprising, in combination, a first pair of levers pivotally connected at a point nearer one end than the other, the longer ends of said levers being inclined in a direction toward each other between the pivot point and the ends, a second pair of levers pivotally connected adjacent their ends, said pairs of levers being pivotally connected on the shorter ends of said first pair and intermediate the pivot point and the ends of the second pair, the shorter ends of said first pair and the free ends of the second pair being provided with gripping jaws, said jaws lying outside the parallelogram formed by lines joining the pivot points.

4. A new article of manufacture consisting of a gripping and squeezing tool formed of strip stock, and comprising a first pair of levers pivoted together nearer one end than the other, and a second pair of levers pivotally connected adjacent their ends, said pairs of levers being pivotally connected on the shorter ends of the first pair and intermediate the pivot point and the ends of the second pair, the shorter ends of said first pair and the free ends of said second pair extending laterally at an angle to the plane of the tool to form gripping jaws lying outside the parallelogram formed by lines joining the pivot points.

5. A new article of manufacture consisting of a gripping and squeezing tool formed of strip stock, and comprising a first pair of levers pivotally connected nearer one end than the other, and a second pair of levers pivotally connected adjacent their ends, said pairs of levers being pivotally connected on the shorter ends of the first pair and intermediate the pivot point and the ends of the second pair, the shorter ends of the first pair and the free ends of the second pair being bent to project laterally from the plane of the tool and forming gripping jaws.

6. The combination claimed in claim 5, in which the line bend forms a small angle with the perpendicular to the center line of the lever arm, whereby the gripping surface of each jaw is substantially tangent to a circle concentric with the point of intersection of lines connecting opposite pivot points.
